[57] CLAIM

The ornamental design for a tote bag, as shown and described.

DESCRIPTION

FIG. 1 is a perspective view from one end of a tote bag according to the present invention;

FIG. 2 is a top plan view thereof;

FIG. 3 is a side elevational view thereof;

FIG. 4 is a side elevational view of the opposite side thereof;

FIG. 5 is a bottom plan view thereof; and,

FIG. 6 is an end elevational view of said one end thereof, the other end being substantially identical thereto.

Fig. 2
